COLLAR MOUNTING FOR
TEAR-STRIP CANS

John Coyle, Baltimore, Md., and William F. Punte, Passaic, N. J., assignors to Continental Can Company, Inc., New York, N. Y., a corporation of New York

Application July 7, 1944, Serial No. 543,857

2 Claims. (Cl. 220—54)

1

The invention relates generally to tear strip or collar cans and primarily seeks to provide a novel form of collar and novel mounting therefor.

In can structures of the character stated, the can body is provided with a tear strip adjacent the upper end thereof which can be wound about a key and thus torn from the can body to separate the upper extremity of the can body and the attached top end closure from the main body of the can thereby to effect an opening of the can. It is customary to provide a collar within and extending from the upper extremity of the can body left by tearing out the tear strip so as to provide an upward extension over which the skirt depending from the removed top closure of the can can be telescoped in order to effect a reclosure of the can. According to the present invention, there is provided a collar including a main cylindrical body portion terminating at its upper extremity in an inwardly directed curl, and at its lower extremity in an inwardly bent portion merging into an outwardly bent portion, and the can body is provided with an outwardly directed bead into which the outwardly directed lower end extremity of the collar is outwardly bent in a manner for anchoring the collar in the upper end of the can and also for so disposing the raw edge at the lower end extremity of the collar as to assure against contact of said raw edge by the hand of a user of the can.

With the above and other objects in view that will hereinafter appear, the nature of the invention will be more clearly understood by reference to the following detailed description, the appended claims, and the several views illustrated in the accompanying drawing.

In the drawings:

Figure 1 is a side elevation and part vertical cross sectional view illustrating a can embodying the invention.

Figure 2 is an enlarged fragmentary vertical cross sectional view illustrating the collar per se.

Figure 3 is an enlarged fragmentary vertical cross sectional view illustrating the collar of Figure 2 mounted in a can of the form illustrated in Figure 1.

In the example of embodiment of the invention herein disclosed, the collar is shown as mounted in a can comprising a body 5, a lower end closure 6 and an upper end closure 7. The can body is provided adjacent its upper end with a bead structure comprising an outwardly extended upper bead portion 8 and an inwardly extended lower bead portion 9. Just above the S-shaped bead portion 8, 9 the can body is scored in the 55 side seam.

2

manner well known in the art to provide a tear strip 10 which when wound about a key may be torn out of the can body to separate the main portion of the body from the upper extremity thereof and effect an opening of the can. When the tear strip 10 is torn out in the manner stated, a skirt 11 is left attached to the upper end closure 7, and this skirt is adapted to be telescoped over the collar which projects from the upper extremity of the main can body in order to effect a reclosure of the can.

Before the collar is inserted in the can it comprises a cylindriform body portion 12 and an inwardly curved upper extremity 13 in the manner illustrated in Figure 2, and this collar is snugly telescoped into the upper end of the can body in position for extending thereabove when the tear strip 10 is torn out in the manner above described. After the collar has been inserted in the upper end of the can body, the lower end portion thereof is mechanically bent outwardly into the upper, outwardly extended bead structure portion 8 with the lower edge thereof abutting the juncture 15 between the outwardly directed bead structure portion 8 and the inwardly directed bead structure portion 9. By thus bending the lower end extremity of the collar 12, it is disposed in the form of a positive stop which engages in the upper bead portion outwardly of the juncture 15 between the bead portions 8 and 9, or in other words outwardly of the diameter of the can body 5 in a manner for definitely placing and preventing a downward displacement of the collar. This placement of the lower end extremity 14 of the collar 12 also serves to present the inwardly directed bead structure portion 9 as an edge guard which will prevent contacting of the raw edge of the collar 12 by the hand of a user of the can. It will be apparent by reference to Figure 3 that the outwardly bent lower end extremity 14 of the collar 12 contacts, as stated, outwardly of the juncture 15 of the bead structure portions 8 and 9 and at such an angle that downward pressure on the collar 12 will tend to expand the collar end portion 14 and thus render even more positive the stop contact of said collar extremity with the S-shaped bead structure 8, 9.

By providing the S-shaped bead structure 8, 9, the individual outwardly and inwardly directed bead portions 8 and 9 can be made relatively shallow so as to avoid the necessity of forming exaggerated bends in the multiple wall thicknesses of the can body at the position of the can body

It is to be understood that the collar herein disclosed may comprise an endless band such as would be formed from a drawn ring, or it may be shaped from a strip joined at its ends in an approved manner. An example of the last mentioned type of collar is shown in the copending application for U. S. Letters Patent Serial Number 543,655, filed by William F. Punte on July 6, 1944, now Patent No. 2,403,192. When collars formed from end joined strips are employed, the joint or seam disclosed by Punte will be found desirable because in this form of joint or seam the multiple thicknesses of collar band metal are disposed only at the central cylindiform body of the collar and no overlapping of wall thicknesses is presented at the upper edge curl or the lower edge bend portions of the collar.

While one form of the invention has been shown for purposes of illustration, it is to be clearly understood that various changes in the details of construction and arrangement of parts may be made without departing from the spirit and scope of the invention as defined in the appended claims.

We claim:

1. In a sheet metal container, a body portion, an upper end closure seamed onto the body portion, said body portion having an S-shaped bead structure adjacent its upper end including an outwardly directed upper bead portion and an inwardly directed lower bead portion, the body portion between said upper bead portion and the closure being scored to provide a tear strip, and a collar snugly fitting within the body and having a main body portion lying opposite and extending above and below the tear strip and a lower raw edge extremity turned outwardly as an anchor

into the upper bead portion and into position for engaging as a collar limiting stop against the upper bead portion outwardly of the diameter of the container body portion.

5. In a sheet metal container, a body portion, an upper end closure seamed onto the body portion, said body portion having an S-shaped bead structure adjacent its upper end including an outwardly directed upper bead portion and an inwardly directed lower bead portion, the body portion between said upper bead portion and the closure being scored to provide a tear strip, and a collar snugly fitting within the body and having a main body portion lying opposite and extending above and below the tear strip and a lower raw edge extremity turned outwardly as an anchor into the upper bead portion and into position for engaging as a positive limit stop against the upper bead portion outwardly of the diameter of the container body portion and in such angular relation to the engaged upper bead portion as to tend upon application of downward pressure on the collar to expand said anchor extension.

JOHN COYLE.

WILLIAM F. PUNTE.
